UNITED STATES PATENT OFFICE.

JOHN McMULLEN, OF BUFFALO, NEW YORK.

UNCOUPLING DEVICE.

Application filed May 22, 1920. Serial No. 383,390.

This invention relates to uncoupling devices for car couplings and has for an object the provision of a simple and efficient device for raising the locking pin of a car coupling by a pulling movement of a hand lever, thereby permitting an operator to actuate the uncoupling device through the application of a force exerted in a direction away from the car and not inwardly between the ends of two adjacent cars that are being uncoupled, with the result that danger of the operator falling between the cars, should he lose his balance, is practically eliminated. A further object of the invention is to provide an exceedingly simple and economical device which develops a powerful leverage on the coupling pin, though with a minimum of effort on the part of the operator.

The invention has for other objects such other improvements or advantages in construction and operation as may be found to obtain in the structures or devices hereinafter described or claimed.

In the accompanying drawings, forming a part of this specification, and showing, for purposes of exemplification a preferred form and manner in which the invention may be embodied and practiced, but without limiting the claimed invention specifically to such illustrative instance or instances.

Figure 1 is an elevational view of an uncoupling device constructed in accordance with the present improvements and applied to the end of a railway car;

Fig. 2 is a top plan view of the same;

Fig. 3 is a detailed vertical section on the line 3—3 of Fig. 1;

Fig. 4 is a detailed vertical section on the line 4—4 of Fig. 1;

Fig. 5 is a view similar to Fig. 1 but illustrating a modification; and

Fig. 6 is a top plan view of the modified form illustrated in Fig. 5.

The same characters of reference indicate the same parts throughout the several views.

In the illustrated embodiment of the invention, the end sill of a railway car formed of the usual channel bar is indicated at 11 and a portion of a car coupling is indicated at 12, said coupling being provided with a locking pin or block 13 which, when lifted, releases the coupling 12 and permits it to uncouple from a companion coupling carried by an adjacent car. The coupling pin 13 is provided at its upper end with an eye

14 which receives one end of the pin-lifting lever, as will be hereinafter set forth.

Bolted to the vertical web of the end sill 11 is a bracket 15 having a depending outwardly and downwardly extending inclined offset portion 16, at the lower end of which portion 16 is formed a U-shaped bearing 17, illustrated more particularly in Fig. 4. Pivoted at 20 between the opposite members 18, 19 of the bearing 17 is one end of the pin operating or lifting lever 21. As shown in Fig. 2 the opposite members 18, 19 of the bearing 17 are spaced sufficiently far apart to allow the pivotal end of the lever 21 to move longitudinally of the car 70 in its bearing 17 and thus accommodate the longitudinal movements of the coupler 12, under draft and buffing stresses. This lever 21 extends diagonally outwardly with respect to the plane of the end sill 11, as 75 shown in Fig. 2 and its contracted free end portion 22 passes freely through the eye 14 of the locking pin 13 of the coupler, the extremity of said contracted portion 22 being formed with an upstanding hook 23 to prevent disengagement of the coupling 13 from the lever 21 on lateral movement of the coupler, although allowing such lateral movement to take place freely without transmitting stresses to the lever 21. The pivotal end of the lever 21 as well as its contracted free end 22 both lie in vertical planes 80 approximately parallel with the vertical plane of the end sill 11, in order to allow the full longitudinally bodily play of the lever 21 under draft and buffing movements of the coupler 12.

Between the aforesaid bracket 15 and the coupling pin 13, a second bracket 24 is also bolted to the vertical web of the end sill 11. 85 This bracket 24 is also provided with a depending outwardly and downwardly inclined offset portion 25, but longer than the offset portion 16 of the bracket 15. Formed at the bottom of the offset portion 25 of the bracket 24 is a U-shaped bearing 26 the opposite members 27 and 28 of which lie in a plane substantially parallel with the main plane of the pin operating or lifting lever 21. Pivoted at 29 in the bearing 26 is the 100 lower end of a lift lever 30. As shown in Figs. 2 and 6, the opposite sides of said lever 30 in the intermediate portion thereof are spaced apart from each other to form an elongated slot 31, through which slot the 105 110

pin lifting lever 21 projects. At its upper end the lift lever 30 is pivoted, as shown at 32, to the hooked end of the hand operated pull lever 33, the inner portion of which lies in substantially the same plane as the lever 30 and the main portion of the pin operating lever 21. At its forward end, the pull lever 33 lies in a vertical plane substantially parallel with the vertical web of the end sill 11, and such parallel portion 34 of the lever 33 passes freely through a bearing 35 supported by a bracket 36 bolted to the vertical web of the end sill 11 at a point more remote from the coupler than the bracket 15. For operating the pull lever 33, the latter is formed at its extreme end adjacent the side of the car with a handle 37.

In the form of the invention illustrated in Figs. 1 and 2, an operative connection between the lift lever 30 and the pin operating lever 21 is established by means of a roller 38 located between and pivoted at 39 to the opposite side members of the lever 30. This roller 38 bears against the bottom edge of the pin operating lever 21, and when the lift lever 30 is rocked in a counter clockwise direction by pulling the hand operated lever 33 outwardly from the side of the car the roller 38 rides along the bottom edge of the pin operating lever 21 and in so doing pushes said lever 21 upwardly, so as to lift the coupling pin 13 and release the coupling 12.

In the modification illustrated in Figs. 5 and 6, the roller 38 may be omitted and a link 40 substituted therefor. The lower end of this link 40 is pivoted at 41 to the lift lever 30 between the opposite side members thereof, and the upper end of the link 40 is formed with a yoke 42 embracing the opposite faces of the pin operating lever 21 and pivoted thereto at 43. On pulling the hand operated lever 33 outwardly from the side of the car, the counter clockwise rocking of the lever 30 causes the link 40 to lift the pin operating lever 21, thereby lifting the coupler pin 13.

The invention as hereinabove set forth is embodied in a particular form of construction, but may be variously embodied within the scope of the claims hereinafter made.

I claim:

1. In an uncoupling device for railway cars, the combination with a car coupler and its coupling pin, of a pin-operating lever pivotally carried by the car independently of the coupler, a pivoted lift lever for actuating said pin-operating lever, and a hand-operated pull rod connected to said lift lever and adapted when pulled outwardly from the side of the car to actuate said lift lever.

2. In an uncoupling device, the combination with a car coupling and its coupling pin, of a pin-operating lever having an opera-

tive connection with said uncoupling pin and pivoted in a bearing supported by the car end independently of the coupling, a lift lever for actuating said pin-operating lever pivoted in a bearing positioned between the bearing of the pin-operating lever and the coupler and located below said last mentioned bearing, a reciprocatory hand operated pull rod connected with said lift lever and adapted when pulled outwardly from the side of the car to actuate said lift lever, and an operating connection interposed between said lift lever and said pin-operating lever, substantially as specified.

3. In an uncoupling device, the combination with a car coupler and its coupling pin, of a pin-operating lever pivotally carried by the car independently of the coupler, a pivoted lift lever for actuating said pin-operating lever, a reciprocatory hand-operated pull rod connected with said lift lever and adapted when pulled outwardly from the side of the car to actuate said lift lever, and means carried by the lift lever adapted to slidably engage said pin-operating lever.

4. In an uncoupling device, the combination with a car coupling and its coupling pin, of a pivoted pin-operating lever having an operative connection with said coupling pin, a pivoted lift lever for actuating said pin-operating lever, a reciprocatory hand-operated pull rod connected with said lift lever and adapted when pulled outwardly from the side of the car to actuate said lift lever, and a roller carried by said lift lever and bearing against the bottom edge of said pin-operating lever, substantially as specified.

5. In an uncoupling device, in combination: a pull rod, a pin operating lever pivoted at one end in a plane below the plane of the eye of the uncoupling device and having its other end slidably engaging in the eye of the pin of the coupler, a lever connected at its upper end to said pull rod and pivoted at its other end in a plane below said pin operating lever, and adapted when pulled around its pivot to have sliding engagement with and thereby raise said pin operating lever.

6. In an uncoupling device, in combination; a pull rod, a pin operating lever pivoted at one end in a plane slightly below the plane of the eye of the coupler pin, a lever connected at one end to said pull rod, and pivoted in a fixed bearing at its other end, said last mentioned lever when operated by said pull rod being adapted to have sliding engagement with and thereby raise said pin operating lever to raise the coupler pin.

7. In an uncoupling device, in combination; a pull rod, a pin operating lever pivoted at one end in a fixed bearing, an actuating lever adapted to slidably engage

said pin operating lever, said actuating lever being pivoted in a fixed bearing, said pull rod and said actuating lever directly connected with each other.

8. A top operating uncoupling mechanism involving a pull rod, a lift lever, and a pin operating lever, the lift lever being adapted to slidably engage said pin-operating lever to cause it to lift the coupling pin to uncoupling position.

9. A top operating uncoupling mechanism involving a pull rod, a pivoted lift lever, and a pivoted pin-operating lever, the lift lever being adapted to bear against the pin-operating lever and slide longitudinally thereof to cause it to move the coupling pin to uncoupling position.

10. An uncoupling mechanism for railway cars involving a pull rod, a lift lever, and a pin operating lever, the pull rod and lift

lever being carried by the car independently of the car coupling and adapted to actuate the pin operating member through a sliding connection therewith.

11. An uncoupling mechanism involving a pull rod, a lift lever, and a pin operating lever, the lift lever having portions embracing the pin operating lever and adapted upon being actuated to slide longitudinally of the pin operating lever to cause the coupling pin to assume uncoupling position.

12. An uncoupling mechanism involving a pull rod, a lift lever, and a pin operating lever, the lift lever having a slot to receive the pin operating lever and adapted upon being actuated to move the pin operating lever to cause the coupling pin to assume uncoupling position.

JOHN McMULLEN.
